UNITED STATES PATENT OFFICE.

EMIL F. HOLINGER, OF NEW YORK, N. Y., ASSIGNOR TO E. CHASE CROWLEY, OF NEW YORK, N. Y.

ANTICREEPING DEVICE FOR RAILWAY RAILS.

Application filed November 17, 1926. Serial No. 148,832.

The invention relates to that class of anti-creeping devices in which a rolling member is interposed between the base-flange of the rail and an adjacent fixed surface on the tie-plate, adapted to engage such edge by a cramping action induced by the creeping movement of the rail relatively to the tie-plate, and it relates more particularly to a tie-plate adapted for such service.

10 The object of the invention is to provide a tie-plate having the required bearing surface for the rolling member and means for holding the latter against vertical escape, which will serve efficiently and may be easily 15 and economically manufactured, and another important object is to provide the tie-plate with such bearing surfaces at each end, thus insuring its proper positioning relatively to the rail and permitting its reversal 20 for further service when worn.

The invention consists in certain novel features of construction and arrangement by which the above objects are attained, to be hereinafter described and claimed.

25 The accompanying drawings form a part of this specification and show an approved form of the invention.

Figure 1 is a plan view showing the improved tie-plate and a portion of a rail supported thereon and engaged therewith.

Figure 2 is a side elevation corresponding to Figure 1, the rail being shown in dotted lines.

30 Figure 3 is a vertical section taken transversely of the rail, on the line 3—3 in Figure 1.

Similar reference numerals indicate the same parts in all the figures.

35 The rail may be of the usual type having the head 5, vertical web 6 and base-flanges 7 and 8, and is supported upon a tie-plate of peculiar construction which is held to the tie, not shown, by spikes 9.

40 The body 10 of the tie-plate has two similar separated ridges 11 and 12 formed thereon parallel with the base-flanges 7 and 8 and receives the latter between them and each has a vertical face next to the rail; the ridge 11 serves as an abutment for the flange 7 to which it lies closely adjacent while the ridge 12 lies a little distance from the flange 8, the space between them receiving a corrugated 45 elliptical roller 13 adapted to engage the ridge and flange.

50 55 The central portion of each end of the

tie-plate is provided with cuts extending from the edge nearly to the ridge, as shown, and the tongue of metal thus formed is folded or bent upwardly upon itself, to form the overhanging lips 14 and 15 projecting inwardly beyond the ridges 11 and 12 and lapping thereupon.

The inner edge of each lip is provided with a centrally located semi-elliptical recess, 16 and 17, serving to permit the introduction of the roller 13, and the space beneath the lip is of sufficient height to permit the roller to move freely therein longitudinally of the base-flange.

50 Spike-holes 18 in the ridge 11 at one end of the tie-plate receive spikes 9 arranged to engage the base-flange 7, and similar holes 19 at the other end serve idly. Spike-holes 20 receive spikes 9 arranged to engage the base-flange 8, and similar spike-holes 21 lie 55 idly beneath the base flange 7.

Thus arranged the spikes 9 introduced through the holes 18 secure the rail to the tie, with the lip 14 overlapping the base-flange 7, and those in the holes 20 hold the 60 base-flange 8 to the tie, with the lip 15 separated a little distance from the base-flange 8. In this condition the roller 13 is introduced through the recess 17 and forced down to engage its corrugations with the edge of 65 the base-flange 8 and with the vertical face of the ridge 12.

A creeping movement of the rail moves the roller beneath the lip 15 sufficiently to prevent its escape through the recess and 70 the same movement insures its frictional grip upon the rail.

75 The lip 14 serves usefully in holding the base-flange 7 against lifting movements but the dual arrangement is intended more particularly to permit the tie-plate to be reversed endwise when the vertical face of the ridge 12 has become worn by the action thereon of the roller 13. Such reversal locates the lip 15 upon the base-flange 7 and 80 presents the unworn vertical face of the ridge 11 to the action of the roller 13. This shifting of tie-plate brings the previously 85 idle spike-holes 19 and 21 into position for service with the base-flanges 7 and 8 by the 90 reintroduction of the spikes 9 and the anti-creeping action of the roller 13 proceeds as 95 before.

The tie-plate in the flat condition with its 100 ridges 11 and 12 is produced by rolling, and 105 110

the spike-holes and the lips 14 and 15 are produced by punching, slitting and bending operations in suitable dies, all of which are simple and may be performed economically.

5 The lips 14 and the idle spike holes may be omitted, thus conditioning the tie-plate to serve without the reversible feature if desired for any reason, as will be understood, but the arrangement shown is preferred.

I claim:—

1. In an anticreeping device, a tie-plate adapted to support a rail, an abutment on said plate adapted to lie against the outer base-flange of said rail, a ridge on said plate lying adjacent to and separated from the inner base-flange of said rail, an overhanging lip formed by folding a portion of said tie-plate upon said ridge, and an engaging 15 rolling member interposed between said ridge and inner base-flange and adapted to lie beneath said lip, the latter having a notch in its edge for the introduction of said rolling member.

2. In an anticreeping device, a tie-plate adapted to support a rail, ridges on said plate one of which is adapted to lie against the outer base-flange of said rail and serve as an abutment therefor, the other of said 20 ridges adapted to lie adjacent to the inner base-flange of said rail and serve as an en-

gaging surface for a rolling member, and an overhanging lip on each end of said plate, formed by folding a portion of said tie-plate upon its adjacent ridge, and one of 35 said lips arranged to lie upon the outer base-flange, and the other of said lips arranged to project toward the inner base-flange above said rolling member.

3. In an anticreeping device, a tie-plate 40 adapted to support a rail, ridges on said plate one of which is adapted to lie against the outer base-flange of said rail and serve as an abutment therefor, the other of said ridges adapted to lie adjacent to the inner base-flange of said rail and serve as an engaging 45 surface for a rolling member, and an overhanging lip on each end of said plate, formed by folding a portion of said tie-plate upon its adjacent ridge, one of said 50 lips arranged to lie upon the outer base-flange, and the other of said lips arranged to project toward the inner base-flange above said rolling member, said tie-plate having spike holes therein arranged to permit its 55 reversal and present either of said ridges in position to coact with said rolling member and said inner base-flange.

In testimony that I claim the invention above set forth, I affix my signature hereto.

EMIL F. HOLINGER.
